TONYS PANTELAKIS, OF LOGAN, WEST VIRGINIA

AUTOMATIC CUT-OFF FOR GAS STOVES

Application filed October 23, 1929. Serial No. 401,850.

This invention relates to an automatic cut-off for gas stoves and the like, the general object of the invention being to provide thermostatically controlled means for closing a circuit to a motor if the flame of the stove should become extinguished for any reason, with means operated by the motor for closing a valve in the supply line so that the supply of gas to the stove will be cut off if the flame should become extinguished.

Another object of the invention is to provide means for opening the valve by hand and for re-setting the thermostatic means by hand after the parts have operated to close the valve.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a side elevation view showing the invention applied to a gas heater.

Figure 2 is a section on line 2—2 of Figure 1.

Figure 3 is a section on line 3—3 of Figure 2.

Figure 4 is a section on line 4—4 of Figure 1.

Figure 5 is a section on line 5—5 of Figure 4.

Figure 6 is a section on line 6—6 of Figure 5.

Figure 7 is a sectional view showing how the insulated contact carrying plate is fastened to the lever.

In these drawings, the letter A indicates a gas heater of the usual construction, though it will, of course, be understood that the invention can be used with any kind of a gas stove or other appliance which uses gas as a fuel.

The letter B indicates a cabinet or casing through which passes a pipe 1 which has one end connected by a tube 2 to the source of

supply and its other end by a tube 3 with the pipe which is connected with the burners of the stove, the usual valve 4 being arranged in the latter pipe for controlling the supply of gas to the burners. A valve 5 is arranged in the pipe 1 within the cabinet and the arm 6 of this valve is connected by a link 7 with an arm 8 which is connected intermediate its ends with the shaft of a motor M arranged in the cabinet. A pin 9 is connected with the lower part of the arm 8 and a bell crank 10 is pivoted in the cabinet and has one arm engaging the pin 9 when the parts are in a position with the valve 5 open. A strip of insulating material 11 is fastened to the arm of the bell crank and contacts the pin. The second arm of the bell crank bears against a switch arm 12 when the parts are in a position with the valve 5 open and the bell crank is connected by a conductor 13 with a terminal of the motor M and the switch arm 12 is connected by a conductor 14 with a terminal of a plug 15 removably arranged in one wall of the cabinet. The other terminal of the motor and the other terminal of the plug are connected by the conductors 16 with the batteries 17 arranged in the cabinet. If desired, the batteries 17 can be eliminated and the conductors 16 connected to a plug 18 which in turn is connected with the house current. When the motor operates, the arm 8 will be shifted to the position it occupies in dotted lines in Figure 5, so that the valve 5 will be closed, and as the pin 9 moves away from the bell crank, the same will drop under the action of gravity into its dotted line position in Figure 5, and the arm 12 will drop against the stop 19 so that the bell crank will be out of engagement with the arm 12 and thus the circuit to the motor will be broken. The parts can be returned to their normal or full line position in Figure 5 by moving a pin 20 passing through a slot 21 in the top of the cabinet from the dotted line position to its full line position, as the inner end of the pin will engage the upper end of the arm 8 and move said arm from its dotted line position to its full line position. This pin is carried by a sliding bar 22 operating in the guideways 23 fastened to the top of

the cabinet adjacent the slot 21. As the arm 8 is moved by the motor, said arm will return the pin to its dotted line position if said pin has not already been moved by hand to such position.

5 A perforated casing 24 is adapted to be placed on top of the stove and said casing has a chamber 25 therein which contains a thermostatic spiral spring 26 which operates 10 a shaft 27 carrying a finger 28. The bottom of the chamber 25 has a hole 29 therein so that the heat from the stove can enter the chamber to act on the spring. An upright 30 is supported on the top of the chamber 25 and a lever 31 is pivoted adjacent one end to said upright. Said lever has a depending part 32 at its free end which normally rests against the top of the chamber 25 and a finger piece 33 of insulating material is connected with the other end of the lever and 20 passes through a slot in the top of the casing so that by depressing this finger piece, the lever will be raised.

25 A pair of fingers 34 is pivoted to the lever 31 and depend therefrom into the path of the finger 28. The upper ends of these fingers are offset, as at 35, so that these portions are normally spaced from the contacts 36 carried by a plate 37 connected with the 30 lever, but insulated therefrom. A contact 38 is arranged in the casing and a contact 39 on the plate 37 normally rests on this contact 38. A second contact 40 is carried by the casing and this contact is connected by a 35 conductor 41 with the upright 30. It will be understood that the two contacts are out of electrical connection, due to the fact that the plate 37 is insulated from the lever and its associated parts, but when either finger 40 34 is swung to the right in Figure 3, the part 35 of said finger will engage a contact 36 and thus the contacts 38 and 40 will be electrically connected together. These contacts 38 and 40 are connected by conductors passing 45 through the flexible tube 42 to the plug 15.

50 It will, of course, be understood that the valve 5 is normally open and while the switch, composed of the parts 10 and 12, are in circuit closing position, the circuit is broken by the parts 35 of the fingers 34 being 55 out of engagement with the contacts 36. When the gas is lighted at the burners of the stove, the heat, acting on the thermostatic device, will cause the finger 28 to move over the usual dial and pass the fingers 34, these 60 fingers simply rocking on their pivots to permit the finger 28 to pass them. If the flame should be extinguished for any reason, the cooling of the thermostatic means would 65 cause the finger 28 to return to normal position and as said finger passes the first finger 34, it will cause the upper end 35 of said finger to engage its contact 36, so that the circuit would be closed through the conductors connected with the battery, the contacts 70

38 and 39, the plate 37, contact 36, finger 34, lever 31, upright 30, conductor 41 to contact 40 through the other conductor and tube 42, conductor 14, to the motor, and through conductor 14, switch parts 12 and 10, conductor 70 13, to the motor and back to the battery by conductor 16. Thus the motor will start to operate and move the arm 8 to close the switch 5 and thus cut off the supply of gas to the burners. As before stated, when the 75 arm 8 is moved, the switch part 10 will move out of engagement with the part 12 and thus break the circuit. If the finger 28 should fail to act on the first finger 34 for any reason, then it will act on the second finger 34. 80

85 After the parts have operated, the parts in the casing 24 can be re-set by pressing downwardly upon the finger piece 33 and the parts in the cabinet B can be re-set by sliding the pin 20 to a position where it will re-set the arm 8 and the parts attached thereto.

90 While I have shown the cabinet B as separated from the stove and the casing 24 on the top of the stove, it will, of course, be understood that these parts can be built into the stove or otherwise arranged with respect to the stove.

95 Thus it will be seen that I have provided simple means for automatically cutting off the supply of gas to a stove if the flame thereof should be extinguished so that danger of asphyxiating persons in a room in which the stove is located, is eliminated.

100 It is thought from the foregoing description that the advantages and novel features of the invention will be readily apparent.

105 It is to be understood that changes may be made in the construction and in the combination and arrangement of the several parts, provided that such changes fall within the scope of the appended claims.

What I claim is:—

110 1. In combination with a gas stove and its supply line, a valve in said line, a motor, an arm connected with the motor shaft, means for connecting the arm with the valve whereby operation of the arm by the motor will close the valve, a circuit for the motor, a chamber, a thermostatic device therein including a finger, said thermostatic device being acted on by the heat from the stove, a pivoted finger in the chamber arranged in the path of the first finger, a contact in the chamber engaged by the pivoted finger when the same is moved by the retrograde movement of the thermostatic finger, means for connecting the pivoted finger and the contact to the circuit whereby the circuit of the motor will be closed when the pivoted finger is in engagement with the contact, a gravity switch in the circuit and means for normally holding the same in closed position by the arm on the motor shaft when the arm is in a position with the valve open, said arm permitting the switch to drop to open position.

- tion when the arm is moved by the motor to close the valve.
2. In combination with a gas stove and its supply line, a valve in said line, a motor, an arm connected with the motor shaft, means for connecting the arm with the valve whereby operation of the arm by the motor will close the valve, a circuit for the motor, a chamber, a thermostatic device therein including a finger, said thermostatic device being acted on by the heat from the stove, a pivoted finger in the chamber arranged in the path of the first finger, a contact in the chamber engaged by the pivoted finger when the same is moved by the retrograde movement of the thermostatic finger, means for connecting the pivoted finger and the contact to the circuit whereby the circuit of the motor will be closed when the pivoted finger is in engagement with the contact, a gravity switch in the circuit, means for normally holding the same in closed position by the arm on the motor shaft when the arm is in a position with the valve open, said arm permitting the switch to drop to open position when the arm is moved by the motor to close the valve, a finger piece for moving the arm to valve opening position and manually operated means for moving the pivoted finger out of the path of the thermostatic finger.
3. In combination with a gas stove and its supply line, a valve in said line, a motor for moving the valve to closed position, a circuit for the motor, a casing associated with the stove, a thermostat in the casing and acted on by the heat from the stove, said thermostat including a finger, a lever pivoted in the casing, a finger pivoted to the lever and depending into the path of the thermostatic finger, the upper end of the pivoted finger being offset, a plate carried by the lever and insulated therefrom, a contact carried by said plate and engaged by the offset part of the finger when the same is moved by retrograde movement of the thermostatic finger, means for connecting the contact and the lever with the circuit whereby the circuit will be closed when the offset part of the pivoted finger engages the contact, a finger piece on the lever and extending through the casing, whereby the lever can be moved to move its pivoted finger above the thermostatic finger and a second switch in the circuit moved to open position when the motor acts to close the valve.

In testimony whereof I affix my signature.
TONYS PANTELAKIS.
